Attorney

UNITED STATES PATENT OFFICE.

LOUIS ROGERS, OF ALBION, PENNSYLVANIA, ASSIGNOR OF SIXTY PER CENT TO W. V. HAMEL, OF ERIE, PENNSYLVANIA.

ROAD PLANER.

Application filed July 11, 1921. Serial No. 483,889.

To all whom it may concern:

Be it known that I, LOUIS ROGERS, citizen of the United States, residing at Albion, in the county of Erie and State of Pennsylvania, have invented certain new and useful Improvements in Road Planers, of which the following is a specification.

This invention relates to road planers and belongs in the class with implements employed for scraping and grading dirt roads and the like. The principal object of this invention is the production of a simple, effective and inexpensive road leveller in which the cutting members are set at about twenty-five degrees angle with the length of the road thus removing the excess dirt over and above that which is left after ruts and low spots are filled towards the center of the road bed until depressions, low spots and other inequalities are all filled and levelled, bringing the road surface to a true grade.

This invention comprises a special construction and arrangement of parts where in the cutting or scraping members are made up of angle irons. The horizontal sides or wings of the angle iron scraping members are deformed or distorted at the points of their connection with the length pieces, in such manner, hereinafter illustrated and explained, as to throw the normally vertical sides or wings of the right angle irons forming the scraping members into an inclined position rearwardly and downwardly. The backward slant resulting from the special distorted construction of the cutting or scraping members permits them to pass over solid obstructions in the roadway without damage to the scraping members themselves or to the motive power, for example, a tractor, which is drawing the planer along the road.

In accompanying drawings which illustrate the special construction and arrangement of the parts of this invention, Fig. 1 represents a top plan view. Fig. 2 is a section lengthwise on the broken line 2—2 of Fig. 1. Fig. 3 is a section lengthwise through one of the side pieces and the successive joints or connections of the scraping members with the side piece, to illustrate the deformed or distorted portion of the horizontal side of the angle iron of which each cutting or scraping member is made. Figs. 2 and 3 are drawn on an enlarged scale.

Throughout the drawings and explanation, the same letter is used to refer to the same part.

Considering the drawings, there are two parallel side pieces A and a usually fashioned of heavy angle iron. In practice I customarily use angle iron measuring four inches by three by five-sixteenths. The four inch leg being arranged vertically with respect to both the scraping members and the length irons or side pieces.

There may be any number of diagonal cutting or scraping members referred to generally by the letter B, and near their ends each scraping member has a rigid connection b with the side pieces.

In the sectional view Fig. 2, it will be observed that the scraping members are formed of right angle iron or steel. That is to say, the sides C and D are formed at right angles with each other in the common manner. The side extending horizontally is marked C and the side arranged slantingly downward and to the rear is marked D. To give the desired inclination to the side D of each scraping member B, the horizontal side or leg of the angle iron B is depressed or recessed at the points where the connections b with the side or length pieces are located. The depressions are designated E, and it will be noted that each depression grows gradually deeper towards the rear. It is the intention to form the depressions of such inclination and depth as to bring the side or leg D of each scraping member B into a slanting position rearwardly and downwardly of 15 degrees from the vertical. This backward slope enables the planer to rise over obstacles in the path without injury to the scraping members.

To insure rigidity and to hold the parts described always in the same position, a brace bar F is secured obliquely at its ends to the side pieces A and a. It will be understood that this invention is not limited to the number of parts herein mentioned, or to their size, or to the material of which they are composed.

Having now described this invention, so far as the particular construction and arrangement of its parts are concerned, it may be stated that in operation it is intended to be drawn along the road with the inclined sides or legs D of the scraping members B in contact with the surface of the road. A

chain G is provided at one end as illustrated in Fig. 1, and a deformed or catch link g or like device engages the chain. The link can be placed in engagement with the chain 5 at any desired point. With the link in the position set out in Fig. 1 the planer will be drawn along with the sides A a in line with the length of the road. But if the link g be attached to the chain nearer the connection 10 of the chain and the side piece A, the scraping members B will assume a position more nearly at right angles to the length of the road, and the side pieces will take up positions somewhat inclined to the line of the 15 road. If, however, the link g be caused to engage the chain G near its connection with the side pieces a, the inclination of the scraping members with respect to the road line will be increased, and the side pieces 20 will again take up positions inclined to the axis of the roadway.

What I claim is:—

1. In a road planer, the combination with longitudinal side pieces, of transverse scraping members formed of angle irons, the said side pieces and scraping members being connected with each other near the ends of the 25 said scraping members, and the horizontal sides of the said scraping members being deformed at the points of connection with the said side pieces whereby the other sides of the scraping members are inclined rearwardly and downwardly.

2. In a road planer, the combination with 30 longitudinal side pieces, of transverse scraping members formed of angle irons and arranged diagonally with respect to the said side pieces, the said side pieces and scraping members being connected together near the 35 ends of the said scraping members, braces extending diagonally between the said side pieces and connected therewith, and the horizontal sides of the said angle iron scraping members being deformed at the points of connection with the said side pieces whereby the other sides of the said angle iron scraping members are inclined rearwardly and downwardly.

scraping members being connected with each other near the ends of the said scraping members, and the horizontal sides of the 40 said angle iron scraping members being deformed at the points of connection with the said side pieces whereby the other sides of the said scraping members are inclined rearwardly and downwardly.

3. In a road planer, the combination with longitudinal side pieces, of transverse scraping members formed of angle irons, the said side pieces and scraping members being connected with each other near the ends of the 45 said scraping members, braces extending between the said side pieces and connected therewith, and the horizontal sides of the said angle iron scraping members being deformed at the points of connection with the said side pieces whereby the other sides of the 50 said scraping members are inclined rearwardly and downwardly.

4. In a road planer, the combination with 55 longitudinal side pieces, of transverse scraping members formed of angle irons and arranged diagonally with respect to the said side pieces, the said side pieces and scraping members being connected together near the 60 ends of the said scraping members, braces extending diagonally between the said side pieces and connected therewith, and the horizontal sides of the said angle iron scraping members being deformed at the points of connection with the 65 said side pieces whereby the other sides of the said angle iron scraping members are inclined rearwardly and downwardly.

In testimony whereof I affix my signature. 70
LOUIS ROGERS. 75
